[73] Assignee: Trans-Aire International, Inc., Elkhart, Ind.

[57] CLAIM

The ornamental design for an interior headliner for a sport roof van, as shown.

[] Term: 14 Years

DESCRIPTION

[21] Appl. No.: 925,873

FIG. 1 is a bottom plan view of an interior headliner for a sport van showing my new design;
FIG. 2 is a right side elevation view thereof, the left side being a mirror image of that shown;
FIG. 3 is a top plan view thereof;
FIG. 4 is a rear elevation view thereof; and
FIG. 5 is a front elevation view thereof.
